DOOR HANGING MECHANISM.
APPLICATION FILED MAY 13, 1913.

Patented Feb. 2, 1915.

2 SHEETS—SHEET 2.

1. A door hanging mechanism comprising a door frame 9, a horizontal track 8 supported by a bracket 10, a lock mechanism, and a curved top on the door frame 9.

UNITED STATES PATENT OFFICE.

JACOB J. BYERS, OF CHICAGO, ILLINOIS, ASSIGNOR TO THE NATIONAL MALLEABLE
CASTINGS COMPANY, OF CLEVELAND, OHIO.

DOOR-HANGING MECHANISM.

1,126,955.

Specification of Letters Patent.

Patented Feb. 2, 1915.

Application filed May 13, 1913. Serial No. 767,250.

To all whom it may concern:

Be it known that I, JACOB J. BYERS, a citizen of the United States, residing at Chicago, Cook county, Illinois, have invented 5 new and useful Improvements in Door-Hanging Mechanism, of which the following is a specification, reference being had to the accompanying drawings, in which—

Figure 1 is an elevation of the side of a 10 car, showing the car door in closed position with my improvements applied thereto; Fig. 2 is a section on lines II—II of Fig. 1; Fig. 3 is a detail of the door in closed position; and Fig. 4 is a detail of the door in 15 slightly opened position.

My invention relates to mechanism for 20 hanging doors, and provides a strong and durable construction for suspending the door and also prevents the door at its upper edge from sagging away or from being forced outwardly from the side of the car or other structure to which it is attached.

My invention also consists in the various 25 parts which I shall hereinafter describe and claim.

Referring to the drawings, A indicates the car and B the car door. The door B is hung from and rolls upon a rail or channel 2, which extends across the front of the 30 door and is attached to the car at its ends by the brackets 3. The door is secured to the rail 2 by the hangers 4 and 5, which are bolted to the door and in which the rollers 6 are mounted on integral trunnions 7. In 35 the rear face of the hangers 4 and 5 are annular openings 8, through which the rollers 6 are inserted. The hangers 4 and 5 have hood-shaped flanges 9 which fit over the top of the door B.

Above the rear edge of the door opening 40 is a bracket 10 which has a downwardly and inwardly extending L-shaped projection 11, adapted to engage outwardly extending lips 12 on the flanges 9 of the hangers 4 and 5. The lips 12 have the ends of their bearing 45 faces beveled, as is shown at 13, to facilitate the engagement of the lips 12 with the projection 11. The bottom of the door is held against outward movement when in 50 closed position by the brackets 14.

In assembling the mechanism the rollers 6 are inserted into the hangers 4 and 5 through the openings 8 and are positioned on the trunnions 7, the hangers are attached 55 to the car door and the rail 2 is then passed

through the hangers and is bolted to the brackets 3. When the door is in closed position, as is shown in Figs. 1, 2 and 3, the lip 12 of the rear hanger 5 will engage the projection 11 of the bracket 10, thus relieving the rail at its unsupported middle section from a portion of the weight of the door B. If the rail has sagged the bracket 10 will raise the roller 5 out of supporting engagement with the rail and will relieve it 60 of all of the weight of the door at this point, as is shown in Figs. 2 and 3. When the door is in opened position the lip 12 of the forward hanger 4 will engage the projection 11 of the bracket 10, and the middle 65 section of the rail 2 will also in this position be relieved from excessive strain from the door at this point. As the rail 2 extends in front of the door, it will prevent the door from becoming detached from the car even though the hangers become broken or loose, and it will also prevent the bottom 70 of the door from swinging outwardly to any considerable distance in case the brackets 14 become broken or inoperative.

It is obvious that various modifications 75 may be made in the construction which I have shown and described herein without departing from my invention.

What I claim is:

1. In door hanging mechanism a rail attached to the structure at its ends and having an unsupported middle section, a door suspended from the rail by a plurality of hangers having roller bearings on the rail, and a bracket on the structure adapted to coöperate with a projection on the door to relieve the middle section of the rail from the weight of the door.

2. In door hanging mechanism a rail attached to the structure at its ends, and having an unsupported middle section, a door suspended from the rail by a plurality of hangers having roller bearings on the rail, a lip on each hanger, and a bracket on the structure having a projection thereon adapted to coöperate with one of said lips to lift one of said hangers out of bearing contact with said rail when the door is closed and with the lip on the other hanger when the door is open, the said projection being adapted in both cases to relieve the middle section of the rail of the weight of the door.

3. In door hanging mechanism, a rail secured to the structure and a door suspended 110

from the rail by a plurality of hangers, each hanger completely inclosing the rail and containing a roller mounted on a trunnion within the hanger, each roller being retained 5 within its hanger by a vertical face of said rail.

4. In door hanging mechanism, a rail secured to the structure, and a door suspended from said rail by a plurality of hangers, 10 each of said hangers completely inclosing the rail and having a roller therein adapted to bear on said rail, each roller being mounted in each hanger on a trunnion integral with the hanger and being insertible into 15 the hanger through an aperture in the face of the hanger opposite to that with which the trunnion is made integral.

5. In door hanging mechanism, a rail secured to the structure, and a door suspended 20 from said rail by a plurality of hangers, each of said hangers completely inclosing the rail and having a roller therein adapted to bear on said rail, each roller being mounted in each hanger on a trunnion integral 25 with said hanger, and being retained in position upon said trunnion by a side of the rail.

6. In door hanging mechanism, a rail secured to the structure, and a door suspended from said rail by a plurality of hangers, 30 each of said hangers having a U-shaped flange extending over the upper edge of the door and downwardly on the rear side thereof, and being adapted to have a supporting engagement with a bracket mounted on the 35 car.

7. In door hanging mechanism, a rail secured to the structure, a door suspended from said rail between the rail and the structure, and a plurality of hangers mounted on 40 said rail and securing the door to the rail, one of said hangers having a portion out of contact with the structure when the door is open, and having a supporting engagement with the structure when the door is closed, 45 and another of said hangers having a supporting engagement with the structure when the door is fully open, and being out of contact with the structure when the door is closed.

8. In door hanging mechanism a rail attached to the structure at its ends and having an unsupported middle section, a door suspended from the rail by a plurality of hangers having roller bearings on the rail, 50 and a bracket on the structure adapted to 55

coöperate with a projection on the door to relieve the middle section of the rail from the weight of the door, said bracket having a portion extending downwardly in front of the edge of the door to prevent said door 60 from bulging outwardly.

9. In door hanging mechanism, a rail supported on the structure by its ends only, a sliding door suspended from a recess in the outer face of said rail between the ends 65 thereof and extending upwardly between said rail and the structure upon which it is supported, a slideable hanger inclosing said rail and mounted on the outer face of said door, and a roller mounted in said hanger 70 and held in position by the rail.

10. A hanger for sliding doors, having a rail inclosing portion, an opening in the rear face of said rail inclosing portion, and a trunnion on the opposite face, a roller adapted to be inserted through said opening into 75 the rail inclosing space and being journaled therein upon said trunnion.

11. In door construction a rail having top and bottom flanges connected by a vertical 80 wall, said flanges and wall forming a longitudinally extending channel, a door, a hanger secured to said door, and having a portion surrounding the rail, a roller journaled within said portion and adapted to 85 roll in the channel of the rail.

12. In door construction, a rail having top and bottom flanges connected by a vertical wall, a door, and a hanger secured to said door, said hanger having a portion surrounding the rail, a roller journaled in said portion between the vertical wall of the rail, and a wall of said portion, said roller being held on its journal by the vertical wall of the rail and being adapted to roll on a flange of 90 95 said rail.

13. In door construction, a door, a rail having top and bottom flanges connected by a vertical wall, said flanges and wall forming a longitudinally extending channel, the 100 recess of which faces outwardly from the door, a hanger secured to said door, and having a portion surrounding the rail, a roller journaled within said portion and adapted to roll in the channel of the rail.

JACOB J. BYERS.
